UNITED STATES PATENT OFFICE.

JAMES ELLIOTT, OF WINGHAM, CANADA.

CLAY PULVERIZER AND SEPARATOR.

SPECIFICATION forming part of Letters Patent No. 712,051, dated October 28, 1902.

Application filed October 11, 1901. Serial No. 78,375. (No model.)

To all whom it may concern:

Be it known that I, JAMES ELLIOTT, a subject of the King of Great Britain, residing at Wingham, in the county of Huron and the 5 Province of Ontario, Canada, have invented certain new and useful Improvements in Clay Pulverizers and Separators, of which the following is a specification.

My invention relates to improvements in 10 machines for pulverizing clay and separating stones therefrom; and the objects of my improvements are, first, to more perfectly pulverize the clay fed to the machine, and, secondly, to more thoroughly separate the stones 15 and other solid impurities of that nature from the clay. I attain these objects by the mechanism illustrated in the accompanying drawings, in which—

Figure 1 is a top view of the machine as it 20 appears after the hopper is removed. Fig. 2 is a side view of the same. Fig. 3 is a vertical section on line 3 3 of Fig. 1, and Fig. 4 is an end elevation.

Similar letters of reference apply to similar parts throughout the several views.

In a suitable frame A, adapted to accommodate the various parts of the machinery, are journaled two pairs of rollers B B and B' B'. The upper pair of rollers B B have their 30 axles journaled in bearings secured to the sills of the frame A. These rollers have their surfaces broken up by coarse helical grooves rectangular in cross-section forming square screw-threads running right-handed on one 35 roller and left-handed on the other roller. The said rollers are set so as to be in contact with one another, and at the contact-line the threads of one roller are opposite the grooves of the other; but the threads do not enter the 40 grooves. At one end the axles project beyond the bearings, and upon these projections are mounted equal spur-wheels C, meshing into each other. The lower or bottom rollers B' B' are in contact with the top rollers, but not with each other, being centered a little farther apart than the top rollers, so that the spur-wheels D, with which their projecting axles are also provided and which mesh with those on the corresponding upper 45 rollers, clear each other. They may be of the same diameter as the top rollers. If not, the

gears on their axles are proportioned to give them the same speed as the top rollers. These bottom rollers B' B' have their surfaces broken by circular grooves, leaving circular ridges of 55 rectangular cross-section pitched closer together, so that about two go to the space of one thread of the top rollers. They are journaled in bearings secured to the lower part of the sills of frame A.

On a shaft journaled in the double bearings is mounted a spur-pinion E, meshing in one of the spur-wheels C of the top rollers, and also a driving-shaft E'. The direction of the motion is such that the top rollers B 65 rotate toward each other from the top downward. The bottom rollers being geared to the top rollers rotate naturally toward each other and toward the top rollers from the bottom upward.

A hopper F surmounts the top rollers. A perforation conforming to and coinciding with the configuration of the converging surfaces of the top rollers is formed in that end of the hopper farthest from the gearing. 75 Through this opening stones and other impurities are ejected.

Movable scrapers G are provided to clear the grooves of the top rollers, one for each roller. They consist each of a curved finger 80 with chisel-pointed end adapted to enter the groove mounted on a collar G', adapted to turn and also to slide on a rod G², which is held parallel to the roller in brackets secured to the side of the sills. The scrapers G are 85 provided with a guard projecting from the collar G', by which guard the scraper may be lifted by turning on the rod G² into any part of the helical groove in roller B and will then follow the latter to the discharge end of the 90 roller, where it will remain inactive until again brought into engagement. A stone or other matter that has become fast in the groove may thus be readily dislodged.

A triangular bar O, disposed beneath the 95 space between the upper rollers, serves to deflect the material outward onto the lower rollers, as will be readily understood from Fig. 3, the lower rollers moving so that their tops do not revolve toward each other, but in the 100 opposite direction.

A plate-scraper H, Fig. 3, is applied to each

top roller B near the bottom. This is held on a longitudinal lever or bar H', secured by a staple H², and the plate H is pressed up against the outer surface of the upper roller 5 B, scraping the clay off that roller into the grooves in the bottom roller B'.

Scrapers I are also provided for the bottom rollers B'. These scrapers are secured to the bottom of the frame of the machine and arranged so as to bear with their edges in the grooves of said rollers.

The effect of the use of four rollers and their specially-prepared surfaces and relative setting is that the lower rollers throw back 15 on the top rollers any stones that may escape the latter, and they may then be worked out at the opening in the end of the hopper or cleared from their grooves by the sliding scrapers, as already described; also, the top 20 rollers force the clay into the bottom rollers, from which it is cleared by the bottom scrapers, also as described already. These

top scrapers are only thrown into engagement with the rollers when occasion requires.

No claim is made in this application to any- 25 thing claimed in my application, Serial No. 52,120, filed March 20, 1901.

Having thus described my invention, what I claim as new is—

In a clay pulverizer and separator, the 30 combination with a receiving bin or hopper F having downwardly-converging sides and a bottom discharge, of a pair of spirally-grooved rollers B B, lower grooved rollers B' B', driving and operating gears C D E, 35 scrapers G G, scrapers H H disposed at right angles to the said scrapers G G, and the fixed vertically-disposed finger-scrapers I I, all substantially as shown and described and for the purpose specified.

JAMES ELLIOTT.
